UNITED STATES PATENT OFFICE.

JOHN JESTER, OF ST. JOSEPH, MISSOURI.

CORK-HOLDER.

SPECIFICATION forming part of Letters Patent No. 369,008, dated August 30, 1887.

Application filed July 1, 1887. Serial No. 243,119. (No model.)

To all whom it may concern:

Be it known that I, JOHN JESTER, a citizen of the United States, residing at St. Joseph, in the county of Buchanan and State of Missouri, have invented a new and useful Improvement in Cork-Holders, of which the following is a specification.

My invention relates to a cork-holder; and it consists in the construction and arrangement of the parts of the same, which will be more fully hereinafter described, and clearly pointed out in the claim.

The object of my invention is to provide a cork-holder constructed of non-oxidizable metal, which holder is constructed in two separate parts, and, being of a pliable nature, is readily attached in connection with the cork of the bottle, as will be readily understood. I attain this object by the device illustrated in the accompanying drawings, wherein like letters of reference indicate similar parts in the several views, and in which—

Figure 1 is a perspective view of a bottle, showing my improved cork-holder in connection therewith. Fig. 2 is a detail perspective view of my improved cork-holder removed from the bottle. Fig. 3 is a top plan view of the blanks used in forming my improved cork-holder.

A indicates a bottle having any suitable form of neck, A', and in connection with which my improved cork-holder B is adapted for use. The cork-holder consists, essentially, of a strip, b, which is adapted to encircle the neck of the bottle A. The strip b is constructed with a transverse slot, b', at its one end and a longitudinal slot, b², formed in its central portion. The one end of the strip b is constructed with a reduced portion, b³, which is adapted to pass through the slot b' when the said strip b is passed around the neck of the bottle. A strip, b⁴, constructed independently of the strip b, is secured to said latter strip at one end and passes over the cork of the bottle, and is secured at its other end to the said strip b when properly adjusted and arranged in connection with said cork. The strip b⁴ is secured to the strip b by passing through the longitudinal slot b², and is bent around and upon the body 50 of the said latter strip b. The opposite end of the strip b⁴ is reduced, as at b⁵, for purposes

which will be more fully hereinafter set forth. The central portion of the strip b⁴ is of greater cross-sectional extent than the two ends, which slightly taper from said central portion. This 55 widened portion of the strip b⁴ is adapted to engage with the top central portion of the cork, and thereby provides a greater bearing-surface for the said cork, which prevents its accidental displacement from the bottle, as will 60 be readily understood.

I preferably construct my improved cork-holder of zinc, which is non-oxidizable, pliable, and tenacious, and is thereby capable of resisting a considerable strain due to the gaseous effect brought to bear on the cork of the bottle; but analogous metals may be used.

In applying my improved invention in connection with the bottle the operation is as follows: The strip b, with the strip b⁴ attached thereto, as hereinbefore set forth, is adjusted in connection with the neck of the bottle, and the said strip b bent around the neck of the bottle, and the end b³ passed through the transverse slot b' and bent over upon this portion 70 of the holder, as shown in Fig. 1. The strip b⁴ is then passed over the top portion of the cork and neck of the bottle, with the enlarged portion thereof bearing immediately upon the top portion of the cork. The reduced end b⁵ 75 of the strip b⁴ is passed under the strip b after it has been bent around the neck of the bottle and the said reduced end b⁵ bent around the outer side of the strip b and back upon the main body of the strip b⁴. By this means it 80 will be seen that an effective fastening is provided for use in connection with the corks of bottles which can be repeatedly used, a portion thereof always remaining in its original adjustment in connection with the neck of the 85 bottle. By reason of its being made in separate pieces one or the other of the two parts may at any time be replaced by new constructions of said parts in case that either one of said parts should become broken and unfit for 90 use. By reason of the pliability of my improved device the same can be bent in securing or releasing the cork, and consequently securing or releasing the holder without danger of breaking the said device.

The novelty and utility of my improved device being obviously apparent and appre-

ciable, it is unnecessary to further enlarge upon the same herein.

Having thus described my invention, I claim—

5 The combination, with a bottle or analogous article, of the strip *b*, passing around the neck of the same and having its ends secured together, and the strip *b*⁴, secured at one end to the strip *b*, passing over the cork or other closure, and having its opposite end bent

around the meeting ends of the strip *b*, substantially as set forth.

In testimony that I claim the foregoing as my own I have hereto affixed my signature in presence of two witnesses.

JOHN JESTER.
